WINDOW SASH LOCK

Bertram F. Cline, Los Angeles, Calif.

Application October 23, 1935, Serial No. 46,307

2 Claims. (Cl. 292—60)

This invention relates to window-sash locks, and particularly to a sash lock for double-hung windows.

The general object of the invention is to provide a window-sash lock, by means of which the sash of a window may be locked closed or open, or partly open in such position as to provide for ventilation, but not sufficient space for a burglar to crawl through the window into the house, thus providing for ventilation through the window, while preventing the entrance of a burglar therethrough.

Other objects and advantages will appear hereinafter as this specification progresses.

The invention is illustrated in the annexed drawing, which forms a part of this specification, and in which,

Fig. 1 is an inside elevation of a double-hung window with my lock applied to the sash thereof, and showing the sash locked in closed position by my lock.

Fig. 2 is a view like Fig. 1, except that the sash are shown locked partly open by my lock, in such position as will provide ventilation through the window, but not sufficient space for a burglar to crawl through the window.

Fig. 3 is an enlarged front view of my lock shown in locking position on a window sash, a fragment of the sash being shown in elevation and a fragment of the window frame and lock sockets in said frame being shown in section.

Fig. 4 is an end view of my lock shown on a sash.

Fig. 5 is a rear view of my lock.

Fig. 6 is a front view of my lock, shown in unlocked position with the lock bolt sleeve shown in section.

Fig. 7 is a horizontal section taken on line 7—7 of Fig. 3.

Fig. 8 is a transverse vertical section of my lock taken on line 8—8 of Fig. 3.

Fig. 9 is a transverse vertical section of my lock taken on line 9—9 of Fig. 6.

Referring more particularly to the drawing, in which corresponding parts are designated by the same reference characters in all the figures, I designated a double-hung window comprising a frame 2, with a sill 3, a lower sash 4 and an upper sash 5, one side 6 of said frame being provided with a plurality of vertically spaced openings 7 in its inner side. One of my locks, generally designated 10, is secured on the inside of the lower sash 4, near the upper end of said sash, and another of my locks is secured on the inside

of the upper sash 5 near the lower end of said sash.

My lock includes generally a plate 11, a slide bolt 12, a spring 13 for said bolt, and a metal sleeve 14, there being one of said sleeves fitted in each of the window-frame openings 7. The plate 11 is formed with a flange 15 bent outwardly from its outer end at right angles thereto, which flange is provided with a bolt opening and bearing 16, through which the outer end portion of the slide bolt 12 extends. The plate 11 is also formed with a depression 17 in its front side or face adjacent its inner end, and is provided with a horizontal slot 18 and a vertical slot 19 at the inner end of said horizontal slot, in the rear wall of said depression. On the rear side of the rear wall of the depression 17 is secured a sleeve bearing 20 in which is slidably fitted the inner end portion of the slide bolt 12, into which sleeve bearing lead the slots 18 and 19, said sleeve bearing being notched at its inner end adjacent the rear wall of the depression 17 to form stops 21 for an arm 22 on the inner end of said slide bolt, which arm is formed on its outer end with a thumb piece 23, and is adapted to extend through the slot 18, when the bolt 12 is in locking position (Figs. 3, 7 and 8) and through the slot 19, when the bolt is in unlocked position (Figs. 6 and 9). The thumb piece 23 is formed with extensions 24, at opposite sides respectively of the arm 22, which extensions extend over the front of the rear wall of the depression 17, above and below the slot 18, when the bolt 12 is in locking position (Figs. 3, 7 and 9), and said arm 22 is adapted to engage one of said stops 21 on the sleeve bearing 20, when the bolt 12 is in unlocked position and said arm is swung either up or down within the slot 19 (Figs. 6 and 9). The front edge or surface 25 of the thumb piece 23 may be curved in an arc described from the center of the bolt 12 (Figs. 8 and 9) so that neither extension 24 of the thumb piece 23 will be swung out beyond the front face of the plate 11 when the other extension is swung into the slot 19 for holding the bolt 12 retracted or in unlocked position (Figs. 6 and 9), thus keeping said front edge of said thumb piece within the depression 17 and within the front face of the plate 11 at all times so that it will not strike against the outside of the lower sash when the lock is secured on the inside of the upper sash. The bolt 12 is formed with an annular shoulder 26 between its ends and the spring 13 surrounds said bolt between said shoulder and the forward end of the sleeve bearing 20

for projecting the bolt forwardly and its forward end into a sleeve 14 within an opening 7 in one side of the window frame (Figs. 1, 2, 3 and 4). The plate 1 is provided with openings 27 in the 5 rear wall of the depression 17 to receive screws 28 for securing the lock to the inside of the sash 4 or 5 (Figs. 5, 6 and 3), and the flange 15 of the plate 11 is provided with openings 29 to receive screws 30 for securing said flange to a side edge 10 of either of said sash (Figs. 8, 9 and 4).

The operation, uses and advantages of my invention are as follows:

When the sash 4 and 5 are closed, as shown in Fig. 1, the arm 22 of the lock on each sash is 15 swung into horizontal position, by applying one's thumb to the arcuate edge 25 of the thumb piece 23, so that said thumb piece is positioned with its extensions 24 outside of the slot 19, whereupon the spring 13, acting against the bolt shoulder 26 and the forward end of bearing 20, projects the forward end of said bolt into a sleeve 14 within an opening 7 in the side 6 of the window frame 2, the arm 22 sliding forwardly 20 through the slot 18, and said sash are thereby 25 locked in closed position.

To unlock a sash the thumb is applied to the thumb piece 23 and the bolt 12 pushed to the right, as shown in Figs. 3 and 7, until its forward end is withdrawn from a sleeve 14 in 30 an opening 7 in the window frame, and the thumb piece and arm 22 are then swung up or down, so that one of the extensions 24 of the thumb piece projects through the slot 19, in which position said extension engages the 35 left side of said slot, as shown in Figs. 6 and 9, under the influence of the spring 13, and holds the bolt 12 withdrawn from said sleeve 14. The sash is now unlocked and may be opened.

When it is desired to lock a sash partly open 40 to admit air into a room, but not open sufficiently to admit a burglar through the window, the sash being open in such position, the thumb is applied to the arcuate edge 25 of the thumb piece 23, and said thumb piece and arm 22 are swung up or down, until the extensions 24 of the thumb piece are withdrawn from the slot 19, as shown in Fig. 8, in which position of the thumb piece the bolt 12 is projected by the spring 13 into the sleeve 14 in an opening 7 in the side 6 of the window frame, as shown in Fig. 3, thus locking the sash in a position as shown in Fig. 2 of the drawing. In the open position of the sash, as shown in Fig. 2, it will be observed that the open position of the sash is such that air may be admitted through the window under the lower sash and over the upper

sash, but the space between the lower edge of the lower sash and the window sill 3, and the space between the upper edge of the upper sash and the upper member of the window frame are too narrow to admit a burglar through said spaces into the house.

My lock is placed on the lower sash high enough above its lower edge to prevent a burglar from reaching through the space between the lower edge of the sash and the window sill 3 and unlocking the lock, while my lock is placed on upper sash low enough below its upper edge to prevent a burglar from reaching through the space between the upper edge of said sash and the upper member of the window frame and unlocking said lock.

The highest point of the arcuate outer edge of the thumb piece 23 rests within the depression 17 and within the front face of the lock plate 1, so that the lock on the upper sash will have its thumb piece in such position that it will not strike against the lower sash when the sash are moved into overlapping relation.

I claim:

1. A window sash lock comprising a plate 25 formed with a depression therein and a sleeve-bearing at the rear of said depression opening at its front side into said depression, and said plate being bent at one end to form an end flange, said flange being formed with a bearing 30 in alignment with said sleeve-bearing, a slide bolt mounted to slide in said sleeve-bearing and through said flange-bearing, and an arm on said bolt projecting through said open side of said sleeve bearing into said depression.

2. A window sash lock comprising a plate 40 formed with a depression therein and a sleeve-bearing at the rear of said depression opening at its front side into said depression, and said plate being bent at one end to form a flange, 45 said flange being formed with a bearing in alignment with said sleeve-bearing, a slide bolt mounted to slide through said sleeve-bearing and said flange-bearing, said bolt being formed with a shoulder; a spring surrounding said bolt and bearing at its ends respectively against said shoulder and against one end of said sleeve-bearing, and an arm on said bolt projecting through the open side of said sleeve-bearing into said depression, said depression being formed 50 with a slot into which said arm is swung when said bolt is retracted against the tension of said spring, so that said arm will engage one side of said slot to hold said bolt retracted and against the expansion of said spring.

BERTRAM F. CLINE. 55
